Primary Examiner — Rhea Shields(74) *Attorney, Agent, or Firm* — Dorton & Willis, LLP(57) **CLAIM**

The ornamental design for a package for bathing articles, as shown and described.

DESCRIPTION

FIG. 1 is a front perspective view of our new package for bathing articles design;

FIG. 2 is a front elevation view thereof;

FIG. 3 is a rear elevation view thereof;

FIG. 4 is a right-side elevation view thereof;

FIG. 5 is a left-side elevation view thereof;

FIG. 6 is a top plan view thereof;

FIG. 7 is a bottom plan view thereof;

FIG. 8 is an exploded front perspective view thereof in a first arrangement;

FIG. 9 is an exploded front perspective view thereof in a second arrangement; and,

FIG. 10 is an exploded front perspective view thereof in a third arrangement.

The broken dash lines shown in the drawing views illustrate portions of the package for bathing articles that form no part of the claimed design.

1 Claim, 10 Drawing Sheets(56)
